UNITED STATES PATENT OFFICE.

EDGAR C. GEORGE, OF NORWOOD, OHIO, ASSIGNEE TO ALLIS-CHALMERS MANUFACTURING COMPANY, OF MILWAUKEE, WISCONSIN, A CORPORATION OF DELAWARE.

CORE FOR ELECTRICAL APPARATUS.

Application filed December 27, 1926. Serial No. 157,043.

This invention relates in general to electrical apparatus, and it has more particular relation to features of construction of the cores of such apparatus which effectively contribute to reduce the losses occurring in such cores during the operation of the apparatus.

In the assembly of cores of electrical apparatus, it has been the practice to utilize relatively thin and varnished core laminæ for the purpose of reducing the eddy current losses in the core, and to assemble and hold these core laminæ in assembled relation through the use of spaced clamping bolts. However, these clamping bolts along with the securing means therefor, such as nuts, riveting or the like, when in operative position, especially in dynamo-electric machines where the element is made up of core laminæ clamped between rigid end heads which serve as or constitute the essential support for the core member, cause the laminæ to bear flatwise against each other with such pressure as to cause undue reduction of the resistance between adjacent laminæ and thus undue increase in the eddy current losses due thereto.

The present invention contemplates and includes a design and construction which embodies the advantages of reducing eddy current losses through utilizing thin core laminæ, and also securing the laminæ in assembled relation in a mechanically satisfactory manner, but with such increased resistance of the path between adjacent laminæ as results in considerably reduced eddy current losses, while permitting economies in the matter of cost of manufacture.

It is an object of the present invention to provide an improved design and construction of cores for electrical apparatus of the type assembled from relatively thin laminations, which provides ample security in the matter of mechanical assembly and construction and increased advantages in the matter of electrical efficiency.

It is a further object of the present invention to provide an improved design and construction of apparatus of this character, wherein the pressure exerted on the core laminæ for holding the same in assembled condition is not fully applied throughout normal flux-carrying portions of the laminæ.

It is a further object of the present invention to provide an improved design and con-

struction of apparatus of the above character, wherein the pressure exerted on the laminæ in holding the same in assembled condition is applied to the full extent on portions of the laminæ outside of the normal flux-carrying portions thereof, permitting the latter portions to bear one against another with reduced pressure.

These and other objects and advantages are attained by the present invention, various novel features of which will be apparent from the description and drawings, disclosing an embodiment of the invention, and will be more particularly pointed out in the claims.

In the drawings:

Fig. 1 is an end view, with parts broken away, of a dynamo-electric machine embodying features of the present invention.

Fig. 2 is a fragmental sectional view in the plane of the line II—II of Fig. 1.

Fig. 3 is a view in elevation of a detail of the apparatus shown in Figs. 1 and 2.

In accordance with the drawings, a dynamo-electric machine, which may be considered an induction motor, of the open stator frame type, is shown as having the stator frame made up of two spaced end heads 10, 12, preferably of cast steel, and the core 13 of the stator is made up of a bundle of thin annular core laminations, preferably with spaced projections 14 at the outer periphery, as indicated, these core laminæ being held clamped in operative position between the end heads 10, 12 by bolts 15 or the like passing through alined apertures in the end heads and the peripheral projections 14 on the core laminæ. These peripheral enlargements 14 on the core laminæ are of such size as to form a substantial bearing or supporting area for the clamping bolts 15 passing through apertures in the enlargements of such size as to just receive these bolts, the apertures being preferably wholly outside of the edge of the normal flux-carrying path through the core.

The bolts 15 may be considered as including a head portion cooperative with the outer side of the end head 10, and a nut 16 threaded on the opposite end of the bolt is cooperative with the outer side of the end head 12, preferably along conical surfaces, when the parts are drawn up by the nut 16 on the bolt, this nut being preferably riveted over the bolt at this time.

In the ordinary construction of a machine of this general character, the rotor comprises a core 23, made up of laminæ assembled and clamped between end plates, and 5 a winding 24, of the squirrel cage type, having its induced portions disposed in slots of the core. The shaft of the rotor is supported in bearings 25 formed on end bells or housings 26 carried by the end heads 10, 12; 10 and the motor is supported by feet, preferably cast integral with the end heads 10, 12 of the stator.

The ordinary commercial practice in the matter of the construction of cores, for dynamo-electric machines of the laminated core type has heretofore been to provide a bundle of thin sheet steel laminæ which are formed to the desired shape, the laminæ being varnished usually by dipping in an insulating varnish bath. These laminæ are assembled and clamped between end heads to provide the desired degree of mechanical compactness and support of the assembled core. However, even with the clamping 15 bolts and apertures therefor in the peripheral enlargements formed on the core laminæ radially beyond the active flux-carrying portion of such laminæ, in clamping these laminæ or punchings against each other so as to provide a desirable and secure mechanical arrangement, sufficient pressure must be exerted between the flux-carrying portions of adjacent laminæ to reduce the resistance between such laminæ, thus causing increased 20 eddy current losses.

In order to avoid this objectionable feature of the described prior art construction and also to secure an equally satisfactory and even more desirable construction at no appreciable increase, and usually at a considerable decrease, in cost of manufacture, these laminæ, instead of being clamped tightly one against another throughout substantially their full area, are so assembled 40 as to be separated into small bunches or groups spaced apart by thin separators or spacers 31 disposed about and held in position on the clamping bolts 15 which pass through apertures in the peripheral enlargements 14 of the laminæ. These spacers 31 are preferably of substantially the same size and shape as the peripheral enlargements 14 of the laminæ, with sufficient material about the apertures in the spacers to permit the latter to maintain themselves on the bolt 15. These spacers 31 may be of metal, such as 50 steel, but they are preferably of insulating material, such as paper or fiber, for the latter has the effect of reducing the resistance of any path of eddy currents through the laminæ at these points.

With the desired number of laminæ assembled with thin spacers 31 disposed in position about or upon the clamping bolts 55 15 at short intervals throughout the length

of the core to divide the latter into small groups of laminæ, it is possible to exert the desired clamping pressure on the laminæ and end heads between which the laminæ are secured, to insure the desired mechanical strength and security of the assembled core; and this desired clamping pressure and mechanical security is attained without the necessity of causing the active or normal flux-carrying portions of the laminæ to bear on or against each other with such pressure as reduces the resistance of the path between adjacent laminæ to the point of unduly increasing eddy currents and core losses.

In commercial practice involving the use of core laminæ of a thickness probably between .010 inches and .025 inches, especially desirable results have been secured with the spacers 31 of paper about .013 inches in thickness disposed about .375 inches apart, that is, thus forming groups of laminæ approximately .375 inches thick.

A very substantial manufacturing economy is associated with the use of the present invention, by reason of the fact that unvarnished core plates or laminæ may now be used in accordance with the present invention with the same and even better results as to operating efficiency in the matter of core losses than with varnished core laminæ assembled and held together in accordance with the prior commercial practice wherein the full clamping pressure used for securing the laminæ in assembled condition was exerted over substantially the full area of the active flux-carrying portions of the laminæ.

It should be understood that the invention claimed is not limited to the details of construction and design described herein, for various modifications within the scope of the claims will occur to persons skilled in the art.

It is claimed and desired to secure by Letters Patent:

1. In a core for electrical apparatus, assembled core laminæ provided with circumferentially spaced peripheral enlargements, enlargements on several laminæ being axially aligned, spacing devices disposed between certain of said laminæ at portions thereof adjacent said peripheral enlargements and extending inwardly therefrom to an inappreciable extent into the active flux-carrying path through said core, and means for clamping said laminæ together in a mechanically secure condition, said clamping means being associated with the peripheral enlargements of said laminæ and said spacing devices whereby the normal flux-carrying portions of said laminæ are permitted to bear one against another with less pressure than the peripheral enlargements of said laminæ.
2. In a core for electrical apparatus, as-

sembled core laminæ provided with circumferentially spaced peripheral enlargements, enlargements on several laminæ being axially alined, thin spacers between the peripheral enlargements of certain adjacent ones of said laminæ, and clamping means for said laminæ associated with the peripheral enlargements of said laminæ and said spacers and effective to clamp said laminæ in assembled condition with a less degree of compression between the normal flux-carrying portions of said laminæ than between the peripheral enlargements thereof.

3. In a core for electrical apparatus, assembled core laminæ provided with circumferentially spaced and apertured peripheral enlargements, enlargements on several laminæ being axially alined, thin apertured spacers between the peripheral enlargements of certain adjacent ones of said laminæ, and clamping bolts passing through alined apertures in the peripheral enlargements of said laminæ and said spacers and effective to clamp said laminæ in assembled condition with a less degree of compression between the normal flux-carrying portions of said laminæ than between the peripheral enlargements thereof.

4. In a core for electrical apparatus, assembled core laminæ provided with circumferentially spaced and axially alined peripheral enlargements, thin spacers between certain adjacent ones of said laminæ and cooperative with substantially only the peripheral enlargements of said laminæ, and clamping means associated with the peripheral enlargements of said laminæ and said spacers and operative to secure said laminæ in assembled condition with a less degree of compression between the normal flux-carrying portions of said laminæ than between the peripheral enlargements thereof.

5. In a core for electrical apparatus, a pair of spaced and apertured end plates, assembled core laminæ provided with circumferentially spaced and apertured peripheral enlargements, enlargements on the several laminæ being axially alined, thin apertured spacers between the peripheral enlargements of certain adjacent ones of said laminæ, and clamping bolts passing through alined apertures in said end plates, the peripheral enlargements of said laminæ and said spacers and effective to clamp said laminæ in assembled condition with a less degree of compression between the normal flux-carrying portions of said laminæ than between the peripheral enlargements thereof.

6. In a dynamo-electric machine, a pair of spaced end heads, core laminæ provided with peripheral enlargements beyond the normal flux-carrying path of the laminæ assembled between said end heads, spacers between the peripheral enlargements of certain of said laminæ, and means associated with the

peripheral enlargements of said laminæ and cooperative with said end heads for clamping said laminæ in assembled and operative condition between said end heads with a less degree of compression between the flux-carrying portions of said laminæ than between the peripheral enlargements thereof.

7. In a dynamo-electric machine, a pair of spaced and apertured end heads, core laminæ provided with apertured peripheral enlargements beyond the normal flux-carrying path of the laminæ assembled between said end heads, apertured spacers between the peripheral enlargements of certain of said laminæ, and clamping bolts passing through alined apertures in said end heads, the peripheral enlargements of said laminæ and said spacers, said clamping bolts having means associated therewith for causing said bolts to hold said laminæ and spacers in assembled operative condition between said end heads.

8. In a dynamo-electric machine, a pair of spaced end heads, unvarnished core laminæ provided with peripheral enlargements beyond the normal flux-carrying path of the laminæ assembled between said end heads, spacers between the peripheral enlargements of certain of said laminæ, and means associated with the peripheral enlargements of said laminæ, and cooperative with said end heads for clamping said laminæ in assembled and operative condition between said end heads with a less degree of compression between the flux-carrying portions of said laminæ than between the peripheral enlargements thereof.

9. In a dynamo-electric machine, a pair of spaced and apertured end heads, unvarnished core laminæ certain of which are provided with apertured peripheral enlargements beyond the normal flux-carrying path of said laminæ assembled between said end heads, thin spacers between certain of said laminæ and cooperative with substantially only the peripheral enlargements of said laminæ, and clamping means for said laminæ comprising a bolt passing through alined apertures in said end heads and the peripheral enlargements of said laminæ and operative to secure said laminæ in assembled condition between said end heads with a less degree of compression between the normal flux-carrying portions of said laminæ than between the peripheral enlargements thereof.

10. In a core for electrical apparatus, assembled core laminæ having their normal flux-carrying portions substantially uninsulated one from another, spacing devices interposed between groups of said laminæ and bearing upon only a portion of the abutting laminæ removed from the most active part of said flux-carrying path, and clamping means for said laminæ associated therewith and with said spacing devices and

effective to mechanically secure the latter and said laminæ in operative assembled condition while permitting portions of said laminæ out of the zone of full bearing of 5 said spacing devices to bear against one another with substantially less pressure than the portions of said laminæ more directly associated with said spacing devices.

11. In a core for electrical apparatus, assembled core laminæ having their normal flux-carrying portions substantially uninsulated one from another, said laminæ being provided with circumferentially spaced peripheral enlargements, the enlargements of 10 several laminæ being axially aligned, spacing devices interposed between groups of said laminæ in line with the peripheral en-

largements thereof and bearing against the abutting laminæ over an area substantially less than that of the active flux-carrying portion thereof, and clamping means for said laminæ associated therewith and with said spacing devices and effective to mechanically secure the latter and said laminæ in operative assembled condition 25 while permitting portions of said laminæ out of the zone of bearing of said spacing devices to bear against one another with substantially less pressure than the portions of said laminæ more directly associated with said spacing devices.

In testimony whereof the signature of the inventor is affixed hereto.
